COMBINED AUTOMATIC BINGO GAME AND SCOREBOARD

Edward E. Mendonca, Hayward, Calif.

Application September 8, 1950, Serial No. 12,106

Term of patent 14 years

(Cl. D34—5)

To all whom it may concern:

Be it known that I, Edward E. Mendonca, a citizen of the United States of America, residing at Hayward, county of Alameda and State of California, have invented a new, original, and ornamental Design for a Combined Automatic Bingo Game and Scoreboard, of which the following is a specification, reference being had to the accompanying drawing, forming a part thereof.

The single drawing figure is a front perspective view of a combined automatic bingo game and scoreboard, showing my new design.

The dominant features of my design are shown in solid lines and the back of the scoreboard is plain.

I claim:

The ornamental design for a combined automatic bingo game and scoreboard, substantially as shown and described.

EDWARD E. MENDONCA.
